Miles Kimball Catalog dated Late Spring 1998, Showing a Lunker Bass™ Handheld Computer Fishing Game.

Primary Examiner—Prabhakar Deshmukh
Attorney, Agent, or Firm—Oppenheimer Wolff & Donnelly LLP[57] **CLAIM**

The ornamental design for handheld electronic fishing game, as shown and described.

DESCRIPTION

FIG. 1 is a perspective view of a handheld electronic fishing game showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a rear elevational view of an alternate embodiment of a hand held electronic fishing game, with a belt clip; and,

FIG. 9 is a left side elevational of FIG. 8.

The broken line showing of chain is for illustrative purpose only and forms no part of the claimed design.
